UNITED STATES PATENT OFFICE.

JULIUS WIESENDER, OF SAN FRANCISCO, CALIFORNIA.

PROCESS OF PURIFYING ILLUMINATING-GAS.

SPECIFICATION forming part of Letters Patent No. 469,847, dated March 1, 1892.

Application filed April 25, 1890. Serial No. 349,515. (No model.)

To all whom it may concern:

Be it known that I, JULIUS WIESENDER, a citizen of the United States, residing in the city and county of San Francisco, and State of California, have invented certain new and useful Improvements in the Process of Purifying Illuminating-Gas, of which the following is a specification.

My invention has relation to an improved process for improving and purifying illuminating-gas; and its novelty will be fully understood from the following description and claims when taken in conjunction with the accompanying drawings, in which—

15 Figure 1 is an elevation, partly in section, of an apparatus for carrying out my improved process; and Fig. 2 is a detail side elevation of the retort-furnace, which forms a part of the apparatus.

20 Referring by letter to the said drawings, A indicates a retort-furnace, in which are suitably mounted the retorts B, which may be of the ordinary or any approved construction. Preferably mounted upon or embedded in the 25 upper side of the retort-furnace A is a hydraulic main D, which is provided with a suitable feed or filling pipe I and with cocks J J^x for drawing off the collected tar and the water when desirable.

30 Leading from the retorts B at a suitable point therein and extending upwardly are stand-pipes C, which are preferably provided at their upper ends with dip branches C^x, which extend downwardly through the top of the hydraulic main and preferably extend beneath the surface of the water therein. By reason of the hydraulic main D being situated upon the retort-furnace A it will be readily seen that the water in said main will be kept 35 at an even high heat, which heating of the water is essential to the accomplishment of my improved process, as will be presently understood.

40 At a suitable point with respect to the hydraulic main I arrange a cold-water tank G^x, which is connected to the hydraulic main by a pipe E and is provided with a suitable feed-water pipe I' and cocks J J^x for drawing off the water when desirable. By passing the 45 gas from the retorts through the hydraulic

main and from thence through the cold-water tank it will be seen that the gas is successively subjected to the action of hot and cold water.

I have found from experiments that by subjecting the gas to the action of hot and cold water successively a greater amount of tar is removed therefrom and a much richer and purer product is obtained than when the gas from the retorts is passed through hot or cold water alone.

55 Mounted upon the cold-water tank G^x is a purifying chamber G of suitable form, which is surrounded by a water-jacket, as illustrated, to receive the depending wall of the cover G', whereby the chamber is rendered air-tight.

60 As illustrated in Fig. 1 of the drawings, the chamber G is divided into two compartments by a vertical partition-wall G², which extends from the bottom of the chamber to a point near the top thereof, a sufficient space being 65 afforded between the upper edge of said wall and the top of the chamber for the gas to pass from one compartment into another.

65 Formed in the top wall of the cold-water tank G^x and in the bottom of the purifying-chamber G is an opening g³, which establishes communication between the said water-tank and the primary compartment of the purifying-chamber, as better illustrated in Fig. 1 of the drawings.

70 Arranged at a suitable distance apart in the respective compartments of the chamber G are open-work shelves or trays H, upon which is placed a suitable purifying agent (indicated by L) for gathering and retaining the impurities 75 of the gas which passes through said shelves.

75 The purifying agent which I prefer to employ upon the shelves or trays H, and which will be made the subject of another application for Letters Patent, is composed of a mixture of iron planings, borings, or turnings and wet sand in substantially the proportion of one part of wet sand to sixteen parts of the iron shavings or turnings. This purifying

90 compound serves to gather and retain the impurities of the gas without absorbing such impurities, whereby it will be seen that when removed from the purifying-chamber the ingredients of the agent may be readily cleansed 95 by the application of heat and water without 100

being consumed, after which they may be replaced in the trays or shelves.

For the sake of economy I prefer to cleanse the purifying compound by placing the same in the retorts, whereby it will be seen that a major portion of the tar and other matter clinging to the ingredients of said compound will be converted into gas.

Leading from the secondary compartment 10 of the chamber G at a point adjacent the bottom thereof is a pipe K, which discharges at its opposite end into a suitable gasometer, as X.

In operation the gas from the retorts B 15 takes through the pipes C into the hot water in the hydraulic main D, from whence it passes through the pipe E into the cold water in the tank G^x, after which it passes up through the opening g³ into the primary compartment of 20 the purifying-chamber G, and from thence into the secondary compartment of said chamber, from which it is conducted to the gasometer.

In the practice of my invention I do not 25 desire to be confined to the manner described of heating the water in the hydraulic tank, nor do I desire to confine myself to any specific apparatus for carrying out my improved process, although the apparatus illustrated 30 and described is preferable and will be made

the subject of a future application for Letters Patent.

Having described my invention, what I claim, and desire to secure by Letters Patent, is—

1. The process of improving and purifying illuminating-gas, consisting in subjecting the same to the action of hot and cold water or other liquid successively, substantially as set forth.

2. The process of improving and purifying illuminating-gas, consisting, first, in passing the gas through hot water; secondly, in passing the gas through cold water, and, thirdly, in passing the gas through a suitable purifier, substantially as set forth.

3. The process of improving and purifying illuminating-gas, consisting, first, in passing the gas through hot water, then through cold water, and finally through a purifying compound consisting of iron planings and sand in about the proportions stated, substantially as specified.

In testimony that I claim the foregoing I have hereunto set my hand and seal.

JULIUS WIESENDER. [L. S.]
